UNITED STATES PATENT OFFICE.

EDWARD G. SHORTT, OF CARTHAGE, NEW YORK.

IMPROVEMENT IN SHAFT-COUPINGS.

Specification forming part of Letters Patent No. 150,261, dated April 28, 1874; application filed October 4, 1873.

To all whom it may concern:

Be it known that I, EDWARD G. SHORTT, of Carthage, in the county of Jefferson and State of New York, have invented a new and Improved Clamping Device for Cylindrical Surfaces, of which the following is a specification:

In the accompanying drawing, Figure 1 represents a front view of my improved clamping device, and Fig. 2 a vertical transverse section of the same, on the line *c c*, Fig. 1.

Similar letters of reference indicate corresponding parts.

The object of my invention is to produce an improved device for clamping cylindrical surfaces, so that a rigid connection of the same is formed, and their lengthwise sliding also prevented.

This invention will first be fully described, and then pointed out in the claim.

A, in the drawing, represents the axle-shaft or other body with cylindrical surface, on which the pulley-wheel or other object is to be firmly clamped or keyed. The cylindrical body B is cast with an eccentric recess, *a*, by placing a curved wedge or cam, C, in a sand or composition mold, pouring the metal in direct contact with its outer surface, and forming thus a seat for the wedge or cam to slide on along the circumference of the recessed part.

The curved wedge C is of eccentrically-bored shape, of less length than recess *a*, and is provided with grooves *b'*, fitting into corresponding ribs *b*, of body B, to prevent the sliding of the same on the shaft in longitudinal direction. A wedge-shaped key, D, is driven in at the broader end of recess *a*, and forces the wedge or cam C around the axle or shaft A, securing a rigid connection of the parts in either direction. The parts may, however, be quickly and easily detached for repairs or other purposes on taking out key D, which gives play to the eccentric wedge C and shaft A.

A very effective and easily-applied clamping device for cylindrical surfaces is thus produced.

Having thus described my invention, I claim as new and desire to secure by Letters Patent—

The combination, with shaft A and key D, of the cam-piece C, having groove *b'* on its convex edge, and the cam-slotted pulley B, having curved rib *b*, as and for the purpose described.

EDWARD G. SHORTT.
